UNITED STATES PATENT OFFICE.

CHARLES W. MOORE, OF SOUTH BEND, INDIANA, ASSIGNOR TO OLIVER CHILLED PLOW WORKS, A CORPORATION OF INDIANA.

PLOW.

Application filed October 20, 1924. Serial No. 744,532.

This invention relates to a plow construction.

The primary object of the present invention is to provide an improved plow construction which will facilitate the assembling of the various parts which go to make up the plow base with greater accuracy and precision, thereby insuring uniformity in manufacture and assembling and greater efficiency in operation and also affording greater rigidity to the parts of the plow base, particularly the plow point.

A further object of the invention is to provide a plow construction which will assist in properly aligning and locating the moldboard, share and standard, with respect to each other and incidentally strengthening these parts when assembled.

A still further object of the invention is to provide an improved plow construction which will assist the farmer in replacing repair parts, particularly the plow points in a manner to insure correct working of the plow.

These and other objects are accomplished by providing a construction and an arrangement of the various parts in the manner hereinafter described and particularly pointed out in the appended claims.

Referring to the drawings, Fig. 1 is a perspective view of a plow showing the plow point thereof partly disassembled from its associated parts.

Fig. 2 is a perspective view of the standard and land-side of my improved plow construction.

Fig. 3 is a cross sectional view taken on the lines 3—3 in Fig. 1, and

Fig. 4 is a perspective view of the lower side of the plow share or point.

The present invention is directed to an improved plow construction which facilitates the assembling of the various parts of a plow base and eliminates the necessity of using straight edges and squares for properly aligning the various parts of the plow in assembling them.

This construction provides an accurate means for locating the various parts with respect to each other and aids in preventing the breakage of the shares due to ill fitting, and also facilitates the establishment of a

good joint between the moldboard and the plow share which is essential for scouring and proper operation of the plow. I have found that in the assembly of plow bases, the shares which are secured to the standards by bolts may be positioned through a considerable range of adjustment due to looseness between bolts and bolt holes and irregularities in manufacture so that the point of the share or the wing of the share may be elevated or depressed or the point of the share may be deflected laterally.

I have also found that the position of the plow share including the point and wing in relation to the plow base is of vital importance and that the slightest variation in the relation of the point and wing of the share affects the operation of the plow in an unexpected manner. In plows as commonly constructed the moldboard is bolted to the standard and serves to locate the share with respect to the position of the wing and point. I have found that moldboards often become loosened in use and when shares are replaced such shares will be improperly located due to such shifting of the moldboard, with the result that the plow will thereafter work very imperfectly and the defect be almost impossible to diagnose and remedy by the farmer. My invention is designed to overcome these difficulties by providing means for positively locating and supporting the share in relation to the standard so that the strain on the bolts of the share will be relieved as well as the strain on the moldboard and the share under all conditions retained in operative position on the standard independently of the moldboard.

For the purpose of illustration, I have shown my improved plow construction comprising a base or standard 10 which has secured to its rearwardly extending portion 11, by means of bolts 12, a land-side 13. The standard 10 is provided with a downwardly curved surface 14, which is preferably positioned at an inclined angle with respect to the line of travel of the plow and a forwardly curved edge 15. The downwardly curved surface 14 is provided with two upper apertures 16 and a lower aperture 17. Extending downwardly and laterally as a continuation of the curved surface 14 of the

standard 10 is an ear 18, which has a lower straight edge, as shown at 19. Extending outwardly from the downwardly curved surface 14 of the standard 10 and along a line which is a continuation of the straight edge 19 of the ear 18 is an upwardly projecting lug 20. This lug 20 is substantially rectangular in cross section, as shown in the cross sectional view in Fig. 3, and occupies a transverse position with respect to the line of travel of the plow. Mounted on the forward edge 15 and slightly overlapping the curved surface 14 of the standard 10, as shown at 21, is a plow point or share 22. The plow point 22 is provided with the usual laterally extending winged portion 23 which is adapted to have a portion thereof overlapping and lie against the lower portion 24 of the downwardly curved surface 14 of the standard 10. Formed on the rear side of and adjacent the upper edge 25 of the winged portion 23 of the point 22 is a recess or cavity 26, which is adapted to engage and snugly fit the upwardly extending lug 20 of the standard 10 for accurately positioning the point 22 on the standard 10. Formed on the lower side of the winged portion 23 of the plow point 22 and adapted to engage the under side of the ear 18 of the standard 10 is a projection 27 which may be used particularly on cast shares when only one securing bolt is employed to anchor the point or share. The point 22 is further provided on its rear edge with a curved flange 28 which is adapted to be engaged by and seated on the forward curved edge 15 of the standard 10. The plow point 22 is provided with an aperture 29 which is adapted to register with the aperture 17 in the standard 10 for the reception of a counter-sunk bolt for securing the plow point to the standard. When desired more than one of such bolts may be employed. From this construction it will be noted that by positioning the lug 20 at a position substantially transverse to the line of draft of the plow that the plow point is reinforced and strengthened by this lug by reason of the fact that the force acting against the plow point is transmitted directly to the standard without undue strain on the securing bolts. When the plow point 22 is properly secured to the standard 10 in the manner above described the edge 25 is in alignment with the upper edge 30 of the lug 20. When the point is secured to the standard in this position the moldboard 31 may then be positioned with its lower straight edge 32 resting against the upper edge 30 of the lug 20 and co-inciding with the upper edge 25 of the winged portion 23 of the point 22. The forward edge 33 of the moldboard 31 will then be resting against and contacting with the rearward edge 34 of the upwardly extending portion of the point 22. When the moldboard is thus positioned

counter-sunk bolts 35 may be inserted in the registering apertures of the moldboard and the apertures 16 of the standard 10.

From the above description it will be seen that by placing the lug 20 on the standard 10 of the plow and forming a recess in the point therefor, I have provided a construction which permits the positioning of the point of the plow with accuracy and precision on the standard and at the same time produces a lug construction which reinforces and strengthens the plow point in that the lug is arranged substantially transversely with respect to the line of draft, thereby transmitting the force directly from the plow share to the standard, and it will further be noted that the upper or rearward edge of the lug assists in properly locating the moldboard in relation to the standard and the plow point, and firmly secures the moldboard in a relatively fixed position with respect to the other parts.

While in the above specification I have described one embodiment which my invention may assume in practice it will of course be understood that the same is capable of modification and that modification may be made without departing from the spirit and scope of my invention as expressed in the following claims.

What I claim as my invention and desire to secure by Letters Patent is:

1. In a plow, the combination with a standard having a relatively long lug positioned transversely with respect to the line of travel of the plow, of a share having a corresponding recess adjacent one edge thereof for receiving said lug and locating said share with respect to said standard, and a moldboard having one edge engageable with one side of said lug and a corresponding side of said share for locating said moldboard and share with respect to said standard.

2. In a plow, the combination with a standard having a relatively long lug on one side thereof adapted to form an abutment for locating a moldboard thereon, of a share having a corresponding recess adjacent one edge thereof for receiving said lug and locating said share with respect to said standard, and a moldboard having one edge engageable with one side of said lug and a corresponding side of said share for locating said moldboard and share with respect to said standard.

3. In a plow, the combination with a standard, of a share secured to said standard and having a recess therein, a moldboard secured to said standard and contacting with said share, and means including a lug formed on said standard and extending along the line of contact between said share and moldboard for locating said moldboard and share with respect to said standard.

4. In a plow, the combination with a standard, of a share secured to said standard and having a recess therein, a moldboard secured to said standard and contacting with said share, and means including a lug formed on said standard and extending transversely to the forward line of movement of the plow and along the line of con-

tact between said share and moldboard for locating said moldboard and share with respect to said standard. 10

In testimony whereof I have signed my name to this specification, on this sixth day of October, A. D. 1924.

CHARLES W. MOORE.
